UNITED STATES PATENT OFFICE.

CHARLES DICKENSON, OF PORTLAND, OREGON.

PANORAMIC TARGET.

SPECIFICATION forming part of Letters Patent No. 613,855, dated November 8, 1898.

Application filed August 4, 1898. Serial No. 687,744. (No model.)

To all whom it may concern:

Be it known that I, CHARLES DICKENSON, a citizen of the United States, residing at Portland, in the county of Multnomah and State 5 of Oregon, have invented certain new and useful Improvements in Panoramic Targets; and I do declare the following to be a full, clear, and exact description of the invention, such as will enable others skilled in the art to which 10 it appertains to make and use the same, reference being had to the accompanying drawings, and to the figures of reference marked thereon, which form a part of this specification.

15 My invention relates to a novel form of panoramic target; and the object is to provide a simple, instructive, and entertaining device of this character for the amusement of both old and young and one requiring a fair 20 amount of skill in its manipulation and one that will produce both an audible and a visible result as a reward for accomplishing the desired end.

To this end the invention consists in the 25 construction, combination, and arrangement of the several parts of the device, as will be hereinafter more fully described, and particularly pointed out in the claims.

In the accompanying drawings the same 30 reference characters indicate the same parts of my invention.

I have shown in the present drawings the simplest form of my invention now known to me; but I do not wish to be understood as 35 limiting myself to such construction, as it is evident that many changes may be made within the skill of a good mechanic without departing from the spirit of my invention, as hereinafter set forth in the specification and 40 in the claims.

Figure 1 is a front elevation of my panoramic target as it appears ready for use. Fig. 2 is a similar view showing the appearance of the target after the two outside bull's-eyes 45 have been tripped. Fig. 3 is a similar view of the target after the center bull's-eye has been tripped. Fig. 4 is a top plan view. Fig. 5 is a transverse vertical section on the line 5 5 of Fig. 4. Fig. 6 is a rear elevation. 50 Fig. 7 is a longitudinal vertical section on the line 7 7 of Fig. 4.

In the present instance I have chosen for

the panorama the well-known historical incident of the sinking of the United States collier *Merrimac* in the harbor of Santiago de Cuba as being of special interest at the present moment, but of course any consecutive series of disconnected scenes may be employed, and such scenes may be varied from time to time to cater to the public interest in 60 current events.

In Figs. 1, 2, and 3 the fixed panel 1 represents a section of the broadside of a United States battleship, 2 2 the port-holes, and 3, 4, and 5 the projecting muzzles of the midship 65 battery and which constitute the bull's-eyes of the target.

6 denotes the gunwale of the ship, and the fixed panel 7 above it a perspective view of the ocean, while above this in Fig. 1 is seen 70 two independent vertically-movable panels 8 and 9, having depicted thereon the representations of Spanish warships in the foreground and the Island of Cuba in the background, these panels 8 and 9 being operatively connected to the bull's-eyes 3 and 5, respectively, in a manner to be tripped and disappear when said bull's-eyes are forced inwardly, as will be hereinafter more fully explained. When these panels 8 and 9 disappear, as shown in 75

Fig. 2, a single movable panel 10 is seen, which occupies the entire width of the target and which represents the entrance to the harbor of Santiago de Cuba, with the United States collier *Merrimac* in the channel between the two forts. This panel 10 is operatively connected with the central bull's-eye 4, and when the latter is tripped the panel disappears, and, as shown in Fig. 3, a single fixed panel 12 is seen, representing the sunken 85 *Merrimac* on the same scene. At the same time a United States flag 13 is seen waving from a flag-pole on the right, and a small boat 14, in which an officer representing Ensign Hobson, passes from the left across the scene 90 and disappears on the right, and the sound of music is heard as denoting the success of the undertaking represented by the scene.

In the present instance I have shown only three bull's-eyes, and consequently three corresponding movable scenes; but of course this number may be increased or diminished at will.

Referring in detail to the construction, 15

denotes a suitable case or cabinet the parallel sides 16 16 of which form shields for the projectiles directed at the target, and 17 denotes a trough in the base 18 for retaining the 5 spent projectiles.

19 denotes the front board, on the back of which is pivoted a series of vertical levers 20, 21, and 22, the lower ends of which carry the forwardly-projecting pins 23, to which the 10 bull's-eye disks 3, 4, and 5 are fixed, suitable orifices being formed in said front board, as shown, for the pins 23 to extend through.

24 denote leaf-springs fixed to the upper ends of the bull's-eye levers, the tension of 15 which is exerted to hold the bull's-eye disks a short distance from the front board, and the immediate upper ends of said levers terminate in an offset or shoulder 25, which projects into the path of a carriage 26, which has 20 a vertical movement in the guide-flanges 27 27, fixed to the front board, the carriage 26 corresponding to the lever 21, while the carriages 28 and 29 correspond to the levers 20 and 22.

25 30 denotes a longitudinal strip fixed to the base-board beneath the carriages, and 31 a piece of metal fixed to said strip and in line with the port-holes 2 2 2, and it forms the limit-stop or anvil for the carriages to rest 30 upon at the end of their downward movement.

The lower face of each of the carriages forms a hammer which impacts on said anvil when the cartridge is tripped and which explodes a fulminating-cap (not shown) which is conveniently placed upon the anvil through its 35 respective port-hole, and said cap when exploded produces a sound and a flash through the port-hole to simulate the discharge of the gun above it.

40 32 denotes a cross-bar which connects the carriage 28 with the panel 8, and 34 denotes a cross-bar which connects the carriage 29 with the panel 9, while the central carriage 26 is connected to the layer panel 10 by the bar 33.

45 Each of the carriages is encompassed by a rubber band 34^x, the lower end of which is fixed in any suitable manner in the base-board to draw them down when released.

50 The cross-bar 33 is provided with an extension 35, which projects into the path of a lateral arm 36, fixed on the hinged top board 37 of the bellows 38, so as to raise this top board and inflate the bellows when the carriage 33 is raised.

55 39 39 represent the reed-tubes of the bellows, and 40 a weight fixed on the top board, so that when the carriage is released it will instantly descend under the influence of its 60 rubber band, while the bellows closes much more slowly, thereby prolonging the notes or musical sounds represented by the reeds.

41 represents a longitudinal rail extending across the top of the cabinet and which forms 65 a support for the boat 14 to travel on. A rubber band 42 is fixed at one end to the stern of said boat, and its other end is fixed to a

staple in the end wall of the case. A flexible cord 43 is also fixed at one end of said boat, and its other end passes over a guide-pulley 70 44 and is fixed to the arm 36 on the bellows-top. The pulley 44 is fixed on a shaft 45, journaled in the rail 41, and the rear end of this shaft is provided with a crank-pin 46, which extends through the lower looped end 75 of a vertical lever 47, fulcrumed on a fixed pivot 48, and which is laterally oscillated by the rotation of the guide-pulley. An American flag 13 is fixed to the upper end of said lever 47 and which is waved to and fro by 80 the oscillation of the lever.

The operation of the device is as follows: All of the carriages are raised and locked in this position by their respective supporting-levers. This of course raises the vertically-movable scene-panels 8, 9, and 10, the carriage 33 at the same time lifting the top board of the bellows, and by slackening up on the cord 43 allows the rubber band 42 to draw the boat 14 across the scene behind the panel 10. A 90 series of percussion-caps is now inserted through the port-holes and rest upon the anvil-strips 31, immediately beneath the carriages. The target is now ready for use.

On a small scale, when constructed as a toy 95 for children, marbles may be used as the projectiles; but when constructed on a more elaborate scale, for shooting-galleries and the like, of course the bullets used in the cartridges of the guns will then be the projectiles 100 discharged at the target.

The bull's-eye disks 3 and 5 are the first objective points, and when either one of these is struck its respective carriage falls, carrying down with it its appropriate panel and at 105 the same time exploding the cap on the anvil, thereby producing a report and a flash, which appears at the port-hole beneath the target which has been struck. The same effect takes place when the remaining one of the two disks 110 3 and 5 is struck, and when the central disk 4 is struck a like effect is produced, with this addition: The arm 35 on the central carriage 33 is carried from beneath the arm 36 on the top board 37 of the bellows, thus permitting 115 the weight 40 to press the top board down and sound the notes, while at the same time the cord 43, which is attached to the bellows-arm 36, draws the boat 14 across the scene and in doing so rotates the pulley 44, which oscillates the flag, as hereinbefore described.

Having thus fully described my invention, what I claim as new, and desire to secure by Letters Patent of the United States, is—

1. The combination with the carriage 33 125 provided with the arm 35 of the sound-bellows, the arm 36 fixed to said bellows and extending into the path of the arm on said carriage the boat 14 and the flag 13 operatively connected thereto so as to be simultaneously 130 operated by the movement of said bellows, substantially as shown and described.

2. In a panoramic target, the anvil 30, the vertical lever 20 and the bull's-eye disk 3 car-

ried by the lower end of said lever, the carriage 28 adapted to travel to and from said anvil and in the path of the upper end of said lever 20 and a leaf-spring 24 adapted to hold 5 said lever in the path of said carriage substantially as shown and described.

3. In a panoramic target, the fixed anvil 30, the vertically-traveling carriage 28 the lever 20 mounted parallel to the path of said 10 carriage and formed at its upper end with an angular shoulder 25 to engage said carriage, the bull's-eye disk 3 fixed to the lower end of said lever 20, and the panel 8 carried by said carriage substantially as shown and described.
- 15 4. In a panoramic target, the fixed panel 12,

the movable panel 8, the carriage 28, the cross-bar 32 connecting said movable panel and carriage, the anvil 30 fixed in the path of said carriage, the lever 20 adapted to support said panel 8 in position to conceal the panel 12, 20 and the bull's-eye disk 3, carried by the lower end of said lever substantially as shown and described.

In testimony whereof I affix my signature in presence of two witnesses.

CHARLES DICKENSON.
